TOILET AND TOWEL PAPER ROLL AND FIXTURE.

1,085,387.

Specification of Letters Patent.

Patented Jan. 27, 1914.

Application filed March 19, 1913. Serial No. 755,563.

To all whom it may concern:

Be it known that we, ALEXANDER J. LEWTHWAITE and CHARLES W. MORDEN, citizens of the United States, and residents 5 of the city of Portland, county of Multnomah, State of Oregon, have invented a new and useful Improvement in Toilet and Towel Paper Rolls and Fixtures, of which the following is a specification.

10 Our invention relates to fixtures for holding toilet or towel paper put up in the form of oval rolls, and our invention has for its object the providing of a fixture comprising a housing which incloses the roll of paper 15 and so holds the same that there will be no portion of the paper hanging exposed below the fixture; furthermore, we provide for the convenient insertion of the roll in the fixture, also so arrange the holding 20 means that the paper may be torn from the roll sheet by sheet only; and in connection with these features we provide a paper roll formed of an endless strip divided by transverse slits into sheets so that when the 25 roll is secured in the fixture the individual sheets may be readily separated, but the paper can be consumed sheet by sheet only, whereby waste is avoided.

In order to understand these and inci- 30 dental features of our invention, it will be necessary to describe the details entering into the construction of both the fixture and the paper roll.

In the accompanying drawings: Figure 1 35 is a front elevation of the housing of our fixture; Fig. 2 is a transverse vertical section of the housing taken approximately on the line 2-2 in Figs. 3 and 4; Fig. 3 is a longitudinal vertical section taken approxi- 40 mately on the line 3-3 of Fig. 2; Fig. 4 is a longitudinal horizontal cross-section taken approximately on the line 4-4 of Fig. 2; and Fig. 5 shows a sectional view 45 of the top part of our case in similar manner as in Fig. 3, but here the case is shown as made with two integral restraining lugs instead of only one.

Our fixture comprises a housing, *a*, preferably closed on four sides and the top, the 50 front wall of the housing having a hand opening *b*. On the interior at the top of the housing is provided a restraining lug *c*. In the housing is removably secured a core-

plate *d*, which is provided with a spring-controlled latch *e*, and a lug *f*. The side, 55 *a'*, of the housing *a* is provided with a centrally located slot *v*, to accommodate the intrusion of the lug *f* of the core-plate *d*. Said lug is made of some length so as to hold the core-plate from rotating in the 60 housing. The side, *a''*, of the housing, *a*, is made with a slot *w*, to accommodate the intrusion of the spring latch bar *e'*. The upper end of this slot *w* is made with an inclined portion *w'* for the purpose of giving 65 a cam movement to the spring latch *e*. A deeper cavity *w''*, at the end of said inclined portion, acts as a socket into which the bar of the spring latch bolt will be projected so as to lock the core-plate in its correct 70 position until released by the actuation of said spring latch, as indicated in the broken lines of Fig. 3. The side walls are also provided with inspection orifices as *g*. It is convenient to make the core-plate *d* with a 75 restraining lug *h*. Such restraining lug may also be provided as an integral part of the top of the housing, as shown at *h'* in Fig. 6.

i are holes in the core-plate *d*, providing, 80 as usual, for lightening and economy of metal used.

The housing of our fixture is secured to the wall *k* by screws *j*, *j'*.

The paper roll *P*, used in connection with 85 our fixture, must be specially adapted to such use. To this end the top of the roll is provided with V-shaped edge-slits, as *l*, *l*, and with elongated slits, as *m*, *m*, *n*, the axes of which are located in parallel lines, 90 of which one line is alined approximately with the axis of said edge-slits, and the other line is located in front of said axis. Thus, as will be noticed in Fig. 4, the slot *n* is alined with the axes of the slits *l*, *l*, and 95 the slits, *m*, *m*, are located in a line lying some distance in front of the axis of the slit *n*. Furthermore, as will be noticed, the ends of the slits, *m*, overlap the ends of the edge-slits *l*, and the slit *n*. This construction 100 of paper roll is essential in order to insure that the individual sheets may be readily detached from the roll. The roll is provided with the usual paper core *o*. The oval roll is placed on the core-plate *d*, and before 105 the latter is inserted in the housing of the

fixture, the outer end sheet is detached from the paper roll in the first instance. When the first sheet is removed, such sheet, in the act of removing, will be torn loose from the next sheet in the manner indicated by the broken lines, *s*, in Fig. 4. The end *q* of such next sheet of paper will remain in place notwithstanding the tearing loose of the preceding sheet, because the act of so tearing loose will cause a strain only in the direction pointed by the arrow 6 in Fig. 4. When the subsequent sheet is to be removed this is readily done by simply pulling down the detaching ends *q* of the outer sheet of the paper roll, and until such end hangs below the housing, when a pull on said sheet will tear it loose from the subsequent sheet in the same manner as already described.

As is apparent from the description of the operation of our fixture, the detached end *q* of the outermost sheet remains in place until the last sheet of the paper roll has been removed from the paper core *o*.

It is more convenient to provide two restraining lugs, as *c*, *h*, the latter of these may be an integral part of the core plate *d*. This is a construction which may be preferred, since it assures the proper centering of the paper roll *P*. However, the restraining lug *h* may, if preferred, be omitted from the core *d* and provided on the interior and at the top of the housing *a*, as shown at *h'* in Fig. 6. When so constructed it facilitates the proper positioning of the paper roll *P* by making the restraining lug *h'* with the bevel edges both at *t* and *u*, so as facilitate the insertion of such edges in the related edge slit of the paper roll.

We claim:

1. In a fixture for paper roll, the combination of a housing and a core-plate removably inserted therein, the fixture being provided with alined lugs located for insertion in corresponding cut-out portions at the edges of the top of the paper roll inserted in 45 said fixture.

2. In a fixture for paper roll, the combination of a housing and a core-plate removably inserted therein, the housing and the core-plate having respectively a lug, such lugs 50 being alined with each other and located for insertion in corresponding cut-out portions at the edges of the top of the paper roll inserted in such fixture.

3. In a fixture for paper roll, the combination of a housing and a core-plate removably inserted therein, the fixture being provided with longitudinally extending lugs alined with each other and located for insertion in corresponding cut-out portions at the edges 60 of the top of the paper inserted in said fixture.

4. In a fixture for paper roll, the combination of a housing and a core-plate removably inserted therein, the housing and the core-plate being respectively provided with longitudinally extending lugs, and such lugs being alined with each other and located for insertion in corresponding cut-out portions at the edges of the top of the paper roll inserted in 70 said fixture.

A. J. LEWTHWAITE.
